No. 37,009.

Patented June 28, 1904.

UNITED STATES PATENT OFFICE.

ALBERT STEFFIN, OF NEW BEDFORD, MASSACHUSETTS, ASSIGNOR TO THE PAIRPOINT CORPORATION, OF NEW BEDFORD, MASSACHUSETTS.

DESIGN FOR A TRAY.

SPECIFICATION forming part of Design No. 37,009, dated June 28, 1904.

Application filed April 8, 1904. Serial No. 202,247. Term of patent 7 years.

To all whom it may concern:

Be it known that I, ALBERT STEFFIN, a citizen of the United States, and a resident of New Bedford, in the county of Bristol and State of Massachusetts, have invented a new, original, and ornamental Design for Trays, of which the following is a specification, reference being had to the accompanying drawing, forming part thereof.

The figure is a plan of a tray, showing my 10 new design.

What I claim as new is—

The ornamental design for a tray, as shown.

ALBERT STEFFIN.
